AUTOMATIC CARRIAGE RETURN MECHANISM FOR TYPEWRITERS

Frederic W. Le Porin, Brooklyn, N. Y.

Application November 30, 1934, Serial No. 755,316

11 Claims. (Cl. 197—66)

This invention relates to automatic-return mechanisms for carriages of typewriting machines, and provides improvements therein.

The invention provides an automatic carriage-return mechanism which can be applied to typewriters of the kinds in general use (in which the carriages are manually returned) with virtually no alteration of the mechanism of the typewriter, with a minimum of additive parts, and with no alteration of the normal functioning of the typewriter, the automatic-return mechanism functioning collaterally or alternatively with the manual return operation.

The invention further provides automatic carriage-return mechanism which will stall easily when a hand or a finger of the operator, or other object, is in the path of the carriage during its automatic return, to thereby avoid accidental injury to the operator, or to the machine.

The invention further provides a mechanism which may be economically built, comprising in large part metal parts which may be formed by stamping operations, and the parts of which may be assembled with a minimum of special fitting.

The invention further provides a mechanism which will operate satisfactorily notwithstanding moderate deformations of the parts due to rough treatment of the typewriter, inaccuracies of alinement, etc., in assembling the parts, and in attaching the mechanism to a typewriter.

The invention also provides a mechanism which operates easily, without violent shocks, and in which the operation of the elements, following the operation of a key to start the carriage-return and the operation of mechanism for stopping the carriage return, is automatic, instantaneous and timed so as to obtain the best co-action. The improved mechanism provides for the easy disengagement of a clutch under the conditions of its use in such a mechanism.

An embodiment of the invention is illustrated in the accompanying drawings, wherein:

Fig. 1 is a top-plan view of the carriage-return mechanism, with parts of the typewriter structure also shown.

Fig. 2 is a view in side elevation of the carriage-return mechanism, parts of the typewriter also being shown.

Fig. 3 is a view in side elevation of certain of the parts for starting and stopping the operation of the carriage-return mechanism, the parts being shown in the position in which the motor is cut off and also in the position in which they are when the typing mechanism is being used.

Fig. 4 is a view similar to Fig. 3, and showing

the key for starting the operation of the carriage-return mechanism depressed to the position where the carriage-return mechanism is put into operation.

Fig. 5 is a top-plan view of parts illustrated in Fig. 3.

Fig. 6 is a detail view of the long vertical lever shown in Fig. 3.

Fig. 7 is a detail view of the upper horizontal lever shown in Fig. 5.

Fig. 8 is a detail view of a bracket which is attached to the typewriter, and which is provided with pivotal supports for the levers shown in Figs. 6 and 7.

Figs. 9 and 10 are respectively a cross-section and a top-plan view of parts mounted on the movable carriage and on the stationary frame of the typewriter, respectively, which co-act to initiate the stopping of the carriage-return motor, when the carriage has completed its return movement, as determined by the marginal stops of the typewriter, which marginal stops appear in the figures.

Fig. 11 is a top-plan view of the parts of the carriage-return mechanism (including the motor, speed-reduction gearing and clutch) shown at the right in Fig. 1.

Fig. 12 is a vertical sectional view on line XII—XII of the parts shown in Fig. 11.

Fig. 13 is a transverse sectional view on line XIII—XIII, Fig. 12.

Fig. 14 is an end view of certain parts shown in Fig. 12.

Fig. 15 is a vertical sectional view of the drum and associated parts shown at the left of Fig. 1.

Referring to said drawings, the stationary parts of the typewriter to which the carriage return mechanism is attached, or is to be attached, are indicated by the reference letter S, and the movable spring-tensioned carriage by the letter C.

The carriage-return mechanism comprises a frame 10, which is conveniently formed by stamping from a sheet of metal of moderate thickness, and on which most of the parts of the carriage-return mechanism are mounted.

As here shown, frame 10 is conveniently of an L shape and provided with punched portions 12, 13 and 14 which

are designed to fit beneath the feet 15 of the typewriter, and frame 10 may be attached to the typewriter by removing the feet 15, passing the

screws 16 of the feet through the holes in the portions 12, 13 and 14 of the frame, and then

fastening the screws 16 in the threaded sockets therefor in the frame of the typewriter.

There are only two other parts which are required for

attachment to the typewriter. One is the bracket 18 shown in Fig. 8, which is attached to the typewriter by removing the screw 19 (Figs. 1 and 5) which fastens the top-plate of the typewriter 5 to one of the vertical posts of the typewriter frame, passing the screw 19 through the hole 20 provided therefor in the bracket 18, and then replacing the screw 19 to fasten the bracket 18 to the top-plate of the typewriter and the top-10 plate to the vertical post. The other part is a small plate 22 (Fig. 10) provided with a beveled face or cam 23, which plate 22 is formed on or fastened to the adjustable abutment 24 which latter is carried by the carriage C and co-acts 15 with the marginal stop 26 pivotally mounted on the typewriter frame S, as indicated at 27. The bracket 18 is a simple part which may be formed by punching and bending a piece of sheet-metal.

Mounted on the frame 10 is an electric motor 20 30, and adjacent the motor is the housing 32 of a speed-reduction gearing 33, also mounted on the said frame 10. Numeral 34 designates a drum which is connected with the speed-reduction gearing 33 by shaft 36, and which drum 34 has attached thereto a flexible cord or tape 38 which is attached to the movable carriage C, and preferably to the lever L of the line-spacing mechanism on the carriage, the tape at the side of the typewriter passing over a roller 30 40 which is mounted on the bracket 18 which is attached to the typewriter frame.

The motor preferably drives the drum 34 through a clutch 44.

The speed-reduction mechanism 33 preferably comprises shafts 50 and 51 having meshing helical gears 53, 54 thereon. The helical gears are of a type through which motion may be transmitted with equal facility in either direction, and are to be distinguished from worm gears 40 which resist backward turning. Ball thrust-bearings 55, 56 are provided for shaft 53, so that it may turn easily. A ball thrust-bearing 58 is also provided for the gear 54, so that the thrust thereon from the gear 53 will be sustained in a 45 manner which admits of easy turning. The gear 54, in the embodiment here illustrated, being loose on the shaft 51, is maintained against axial movement, and, as all of the thrust is against the bearing 58, a simple device, as a pin 59, may be provided for this purpose. The pin 59 may be fastened on the housing 32, and be arranged so that its inner end projects within a small distance of the side of the gear 54.

The clutch 44, as shown in the embodiment here illustrated, may be combined with the speed-reduction gearing 33. The gear 54 may have fixed thereon a jaw-plate 61, and opposite thereto, and fixed on shaft 51, is a companion jaw-plate 62. The shaft 51 is axially movable in its 60 bearings, and such axial movement, to bring the jaws 61 and 62 into and out of clutching engagement, is effected through suitable means, as a grooved collar 65 fixed on shaft 51, and a two-armed shift lever 66, 67, which may be pivoted in a bracket 68, fastened on the housing 32, as indicated at 69, Figs. 11 and 14. The shift-lever 66, 67 is acted upon by a spring 71 in a direction to move the shaft 51 axially to bring the jaws 61, 62 of the clutch into engagement.

The shaft 36 is conveniently supported at its end adjacent the reduction gearing in a forked bearing 75 engaging a groove in a collar 76 fastened on the said shaft 36, and thereby prevents axial movement of said shaft 36. At its opposite 75 end the shaft 36 is supported on a stud 78, form-

ing part of the drum-support, and hereinafter more fully described. The shaft 36 turns without being subjected to thrust at either end.

The drive-shaft 81 of the motor 30 is preferably connected to the shaft 53 of the speed-reducing gearing 33 through a universal connection 84. The universal connection 84 may have the simple form of two proximate disks 86, 87 fastened on the respective shafts 81, 53, connected by an eccentric pin 88 projecting from the face of one disk and into a notch 89 in the other disk. The drum-shaft 36 is also preferably connected to the shaft 51 of the speed-reducing gearing 33 through a universal connection 92. The universal connection 92 may have the simple form of a 10 disk 93 fixed on the shaft 36 and projecting within a cupped disk 95 fixed on the shaft 51, the two disks being coupled through a pin 96 projecting from the periphery of disk 93 into an elongated slot 97 in the peripheral portion of the cupped 20 disk 95. By providing the universal joints 84 and 92 between the motor 30 and the speed-reducing gearing 33, and between the speed-reducing gearing and the drum-shaft 36, (and also the universal connection 140 hereinafter described) niceties of 25 assembling the parts to obtain easy running are avoided, and the frame 10 on which the parts are mounted can have a moderate distortion due to rough handling, or may have initial irregularities of form, without interfering with or preventing the easy running of the parts of the carriage-return mechanism.

Numeral 100 designates a switch for controlling the flow of current to the motor 30. This switch 100 is conveniently located within the housing 32, 35 as shown in Figs. 12 and 13. The switch comprises a fixed contact 101 and a movable contact 102. The movable contact 102 is carried on a spring-arm 103. Opposite the spring-arm 103 is arranged a pin or projection 104 which flexes the 40 arm 103 when the arm 103 is moved against said pin. The position of the pin 104 with respect to the spring-arm may be made adjustable as by means of a screw-thread connection 107 between it and the housing 32. The switch 100 may be 45 mounted on a plate 105, which is pivotally mounted as indicated at 106, and which plate has an arm 108 having a projection 109 for a purpose hereinafter explained. The plate 105 carrying the switch 100 is acted on by a spring 111 in a direction to bring the arm 103 on which the contact 102 is mounted into contact with the pin 104, and to thereby move the contacts 101, 102, together to complete the circuit to the motor 30. The spring 111 is conveniently attached at one 55 end to the arm 108 of the plate 105, and at its other end to a part fixed on the frame 10.

The position of the projection 104 may be adjusted so that the making and breaking of the circuit to the motor 30 may be timed with relation to the engagement of the jaws of clutch 44. The preferred timing is such that the clutch 44 is partially engaged before the motor begins to turn shaft 50, and the circuit to the motor 30 is broken before or during the disengagement of 65 the clutch 44.

The drum 34 is conveniently mounted on a hollow stud 116 (Fig. 15) fastened upon a bracket 118, fastened to the frame 10, and which bracket 118 may be conveniently formed of stamped sheet-metal. Ball bearings 120, 121 are preferably provided between the drum 34 and its support, so that the said drum may turn easily under the pull of the tape 38 during the return of the carriage C. The outer race of the ball bearing 121 75

may be provided in a part 124, having threaded engagement with the hollow stud 116, as indicated at 125. A binding-screw 127 serves to hold the part 124 against turning after it is in place. The part 124 also carries the stud 18, hereinbefore referred to, which supports the adjacent end of drum-shaft 36.

The drum 34 is also preferably acted upon by a coiled spring 130 (Fig. 15), one end of which is connected to a flange on the drum, as indicated at 132, and the other end of which, as indicated at 133, is connected to a sleeve 134 fastened to the bracket 118. The spring 130 acts in a direction to turn the drum 34 in a direction to maintain a slight tension or pull on the tape 38, so that the pull of the spring 130 on the drum will maintain tautness of the tape 34 throughout all movements of the carriage which occur when the motor 30 is not acting through the drum to effect the return of the carriage.

The drum-shaft 36 is preferably connected to the drum 34 through a universal joint 140, which joint may have the simple form of a disk 142 fixed to shaft 36 and having an eccentric pin 143 thereto fitting into a socket 145 on the adjacent side of the drum. The universal joint 140 allows the drum 34 to be turned easily by the shaft 36, notwithstanding slight inaccuracies in alinement, due to irregularities in frame 10 and other causes hereinbefore referred to.

As a part of the means for controlling the operation of the motor 30, a reciprocatory part or bar 150 is provided. This bar is conveniently in the form of a flat strip extending alongside in the frame of the typewriter, and having limited longitudinal movement. The bar 150 may be supported in simple brackets 152, 153 formed of sheet-metal and attached to the frame 10 of the attachment, the brackets 152, 153 being provided with headed pins 155 which pass through elongated slots 157 in the said bar 150. The bar 150 has therein an elongated notch 160, within which the projection 109 on the arm 108 of the switch 100, extends. The bar 150 also has thereon a pin 162 which extends across the arm 67, as shown in Figs. 12, 13 and 14. The bar 150 also has thereon a pin 164 (Figs. 1 to 5) which is adapted to be engaged by a detent 166 which may be pivotally mounted on the bracket 118, as indicated at 167. The bar 150 also has thereon a pin 170 which is adapted to be engaged by a pawl 172 on a key-lever 175 which is adapted to be struck for effecting the return of the carriage C through the automatic return mechanism hereinbefore described.

The bar 150 is acted on by a predominant spring 180, and the action of the spring is to normally hold the bar in the position shown in Fig. 3 where an abutment 181 thereon rests against a stop 182 fastened on the frame 10 of the attachment. The pin 162 on the bar (Figs. 12, 13 and 14) bears on the arm 67 of the clutch shift-lever, normally holding the clutch parts 61 and 62 in their disengaged position. The notch 160 in the bar 150 also normally engages the projection 109, and holds the switch 100 out of position to complete the circuit to the motor through the action of projection 104 on contacts 101 and 102. The pin 164 on the bar normally lies above the detent 166, and holds it depressed. When the pin 164 on the bar 150 has been engaged by the detent 166, and the detent 166 is thereafter moved to disengage the pin 164 the force of the predominant spring 180 is such as to overcome the force of the spring 111 acting on the arm 108 of the switch

100, and also to overcome the force of the spring 71 acting on the shift-levers 66, 67 of the clutch, and shoot the bar 150 to the position shown in Fig. 3, as hereinafter described.

The key-lever 175 is pivoted as indicated at 183 (Figs. 3, 4 and 5) to a bracket 184 (which is preferably a stamped metal part) fastened to the frame 10 of the attachment. A spring 186 attached at one end to the key-lever 175 and at its other end to an arm 187 on said bracket 184 normally acts to hold said key-lever up, as indicated in Fig. 3. The movement of the key-lever 175 around its pivot is limited by a pin 191 projecting from the bracket 184 into a slot 193 in the said key-lever 175. The pawl 172 is pivotally attached to the key-lever 175, as indicated at 195. The movement of the pawl 172 around its pivot 195 is, however, limited by a pin 197 thereon extending into a slot 198 in the key-lever. The pivotal mounting of the pawl 172 and the shape of the tooth of the pawl enable the pawl to slip quickly out of engagement with the pin 170 after the bolt 150 has been advanced to a position where the detent 166 is able to rise and engage the pin 164. A spring 199 acts on said detent in a direction to turn it to a position to engage the pin 164. The pin 164 may be mounted on a plate 202 which is adjustable with respect to the bar 150, so that the proper timing of the engagement of the pin 164 by the detent 166 following the release of the pin 170 on the bar 150 by the pawl 172 on the key-lever 175, may be effected.

Suitable means for moving the detent 164 to release the bar 150 as the carriage reaches the end of its return movement, and thereby stop the operation of the carriage-return mechanism, are provided. Means suited to the style of typewriter having a marginal stop at the front of the frame, may be as follows: Pivoted on the bracket 18, as indicated at 204, Fig. 3, is a lever 205, and co-acting with said lever 205 is a lever 207 pivoted to said bracket 18, as indicated at 209, Figs. 1 and 5. The detent 166 has thereon a pin 211 which is adapted to be engaged by the end of said lever 205. A spring 213 connected to said lever 205 and to an arm 215 on said bracket 18 normally tends to hold the lever 205 out of the range of movement of said pin 211 on detent 166. The lower end of said lever 205 is, however, made adjustable, so that the action of said lever 205 on the detent 166 may be properly timed. The adjustment may be effected by providing the lever 205 with an extension 220 (Fig. 6) which is pivoted to the lever 205, as indicated at 222, and which is made fast in its adjusted positions by means of a binding-screw 223. Numeral 225 designates a cam-screw by means of which fine adjustments of said extension 220 may be made when the binding-screw 223 is loosened.

In the form of typewriter here illustrated, the lever 207 is held with its end 230 in contact with the pivoted marginal stop 26 on the frame of the typewriter. When the abutment 24 carried by the carriage C is provided with a cam 23, as hereinbefore described, and when this cam 23 makes contact with the marginal stop 26, the said marginal stop 26 is caused to turn rapidly on its pivot. The marginal stop being in contact with the lever 207 at its end 230, imparts movement to the lever 207 around its pivot 209, and the lever 209 acting upon the lever 205, turns this latter lever 205 around its pivot 204, and brings its end against the pin 211 on the detent 166, thus moving the detent out of the path of the pin 164 on bar 150, and thus allowing the predominant spring 180 to

to bring the abutment 181 on the bar 150 against the stop 182, in which position, as hereinbefore described, the motor 30 is deenergized and disconnected.

5 Because of the light and easy running of the mechanism provided by the ball-bearings 55, 56, 58, 120, 121, and the non-binding driving connections through the universal joints 84, 92 and 140, the motor 30 may be one of minimum power 10 for doing the work of returning the carriage, and in practice I make use of a motor having about 1/64 horsepower, or slightly in excess of that required to move the carriage against the opposing force of the carriage spring. This construction 15 and arrangement, especially when combined with the gears (such as the helical gears 53, 54) which transmit motion with equal facility in either direction, has multiple advantages. The shock when the abutment 24 on the carriage and the 20 marginal stop 26 come together is mild. The clutch parts may move instantly out of disengagement under the influence of a comparatively light spring. The motor stalls easily when an 25 obstruction is met by the carriage, damage to the typewriter and injury to persons are avoided, and by reason of the easy reverse turning of the 30 special type of gears which are provided, an object which is caught between the carriage and a fixed part of the typewriter is not held but is easily released. Moreover the force of the blow is small 35 because of the mechanical disadvantage at which the motor works through the speed-reduction gears, and is resilient because of the capability of easy reverse movement of the parts.

35 Operation

To return the typewriter carriage from any position to which it may be advanced by the operation of the type-bar key-levers, the carriage-return key 175 is struck. The position of the parts prior to the striking of the key-lever 175 is illustrated in Fig. 3, and the position of the parts after the striking of the key-lever 175 is illustrated in Fig. 4. When the lever 175 is struck, it moves around its pivot 183, bringing the pawl 172 thereon into contact with the pin 173 on the bar 150. The pawl 172 moves the bar 150 to the right in the drawings, and as the key-lever 175 approaches the limit of its turning 50 movement, the detent 166 rises under the force of its spring 199 to a position behind the pin 164 on the bar 150. At about the same time the pawl 172 slips off of the pin 170 and releases the bar 150, after which the bar is retained by the detent 55 166. Upon the release of the key-lever 175, its spring 188 restores it to its normal position (shown in Fig. 3), the pawl 172 turning on its pivot 195 on the return movement of the key-lever so as to pass over the pin 170.

60 As the bar 150 is projected to the right under the action of the key-lever 175, the edge of slot 160 moves away from the projection 109 on the switch-lever 108 (Fig. 13), and the pin 162 moves away from the arm 67 of the clutch-lever, which 65 allows the shaft 51 to move quickly to the left under the influence of the spring 71, and thereby bring the clutch part 62 into engagement with the clutch part 61. Practically simultaneously with the movement of the shaft 51, but with enough 70 time difference to allow the clutch parts to partially engage before the motor 30 starts, the switch 100 is rapidly turned under the influence of its spring 111 to establish the motor circuit through the contacts 101, 102. The motor thereupon starts, driving the shaft 50 of the speed re-

ducing means 33 through the universal connection 84. The helical gear 53 drives the helical gear 54, and the gear 54 being connected to the shaft 51 through the clutch parts 61, 62 rotates the said shaft 51, and the said shaft 51 through the universal connection 92 drives the drum-shaft 36. The drum-shaft 36 being connected to the drum 34 through the universal connection 140 (Fig. 15) rotates the said drum, winding the tape 38 thereon, and the winding tape 10 pulls the carriage C until the abutment 24 on the carriage is brought to a stop against the marginal stop 26 (Figs. 9 and 10). The tape 38 being connected to the line-spacing lever L on the carriage, however, first moves the lever L to 15 rotate the platen of the carriage C a distance corresponding to the spacing to be made between lines, and thereafter the pull of the tape 38 on the lever L moves the carriage on its return movement, as just described.

20 The action of the carriage-return mechanism is automatically stopped as follows: As the carriage returns to within about one "space" of its limit of movement permitted by the abutment 24 and marginal stop 26, the cam 23 (Figs. 3, 9 and 10) 25 strikes the edge of marginal stop 26, causing it to turn with great rapidity. The turning movement of the marginal stop 26 produces a turning movement of the lever 201, and this turning movement of the lever 201 causes a turning movement of the lever 205. The movement of the lower end of lever 205 against the detent 211 on detent 166 moves the detent out of engagement with the pin 164 on the bar 150, and the bar being thereby released shoots quickly to the left under the influence of the predominant spring 180; and the contact of the edge of notch 160 (Fig. 13) with the projection 109 on the arm 108 turns the switch 100, to move the arm 103 carrying the movable contact 102 away from projection 104, 40 to quickly break the circuit at the contacts 101, 102, and, at about the same instant the motor is disengaged through the clutch by the contact of pin 162 with the arm 67 of the clutch lever, turning said clutch lever, and the engagement of the 45 arm 66 of the clutch lever with the collar 65 on shaft 51 slides the shaft 51 to the right, thereby separating the clutch parts 61, 62.

50 The momentum of the carriage C after the cam 23 comes into contact with the marginal stop 26 to initiate the de-energization of the motor, and after the de-energization of the motor, will carry the carriage to the limit of its return movement permitted by the marginal stop 26. The mechanism will however act to return the carriage to its marginal position from any position short of its fully returned position.

55 The character of the gears 53, 54 (described as helical gears) is of importance to the operation of quickly disengaging the clutch parts 61 and 62. As the abutment 24 on the carriage moves against the marginal stop 26 there is a recoil or force produced which is opposite to the driving force the motor 30. This recoil is transmitted through the drum and shafts 36 and 51, to the clutch parts. The helical gears 53, 54 permit of easy movement in either direction of rotation. The recoil acting on gear 54 tends to produce movement of the gears 53, 54 in an opposite direction to the direction in which they are driven by the motor and this is transmitted to the armature causing it to move in the opposite direction, and therefore instead of the clutch and gear parts being jammed together by the force of re- 70 75

coil, the clutch-parts are free to move away from one another, because the force of recoil can act on the armature of the motor through the helical gears 53, 54, and relieve the pressure on the 5 clutch teeth, and when the pressure of the clutch teeth is so relieved the clutch parts move apart easily and instantly under the action of the spring 180.

In the position of the carriage with the abutment 24 in contact with the marginal stop 26 the carriage-return key 175 may be struck as many 10 times as desired to effect as many increments of the line-spacing as desired, the bar 150 being advanced to effect the energization of the motor 30 and the turning of the drum 34 each time that the key 175 is depressed, and the bar 150 breaking the circuit to the motor 30 almost instantly and in the same movement of the key-lever 175, as the pawl 172 thereon slips off the pin 170 15 and releases the bar to be shot back by its spring 180, the detent 166 in the position of the carriage C referred to being held depressed and out of position to engage the pin 164 on the bar by the pressure of the lower end of lever 205 against the pin 211 on the said detent 166. 20

As the carriage C moves to the left in Fig. 1 in the operation of typing, or as the carriage is shifted back and forth manually, tension is maintained on the tape 38, so as to avoid slack occurring therein, by the spring 130 attached to the drum 34, as heretofore described. The tension of the spring 130, however, is not sufficiently great to actuate the handle L of the line-spacing mechanism. The drum 34 and shaft 36 being disconnected from the motor through the clutch parts 61, 62 at this time, turns most freely under the pull of the spring 130 and offers virtually no resistance thereto. 25

The invention has been illustrated in connection with a typewriter having its marginal stop on the frame of the typewriter in front of the carriage. In other typewriting machines the marginal stops are arranged at the rear of the carriage. Therefore the part of the mechanism from the detent 166 to the cam 23 on marginal abutment 24 is conformed to the particular style of typewriter to which the carriage-return mechanism is applied. 40

The invention may receive other embodiments than that herein specifically illustrated and described. 50

What is claimed is:

1. Carriage return mechanism for typewriters, comprising an electric motor, means for connecting the motor to the carriage of a typewriter, and means for starting and stopping the motor comprising a switch, a reciprocatory bar through which said switch is opened and closed, a spring 55 acting on said bar in a direction to move the bar to switch-opening position, a manual key-lever having a pawl thereon for directly engaging said bar to move it against the tension of said spring to switch-closing position so that said bar may be moved to switch closing position irrespective of the position of the carriage, a detent for retaining said bar, against the tension of said spring, in switch closing position, and carriage actuated means for automatically tripping said 60 detent to release said bar. 70

2. A combination according to claim 1, wherein said tripping means comprises a vertical lever arranged to contact with said detent, and a horizontal movable element arranged to contact with 75 said vertical lever and with a stop on the carriage

of a typewriter, whereby when said carriage-stop strikes said horizontal movable element the detent is operated to release said bar with a minimum of resistance and the switch is opened by the movement of said bar under the action of the spring acting thereon. 5

3. Carriage return mechanism for typewriters comprising an electric motor, means including a clutch for connecting the motor to the carriage of a typewriter, and means for starting and stopping the motor comprising a switch, a reciprocatory bar through which said switch and clutch are opened and closed, a spring acting on said bar in a direction to move the bar to switch and clutch opening position, a manual key lever having a pawl thereon for engaging said bar to move it against the tension of said spring to switch and clutch closing position, so that said bar may be moved to switch and clutch closing position irrespective of the position of said carriage, a detent for retaining said bar, against the tension of said spring in switch and clutch closing position, carriage actuated means for automatically tripping said detent to release said bar, and means for mounting said return mechanism on a typewriter. 10 15 20 25

4. A combination according to claim 3, wherein said tripping means comprises a vertical lever arranged to contact with said detent, and a horizontal movable element arranged to contact with 30 said vertical lever and with a stop on the carriage of a typewriter, whereby when said carriage-stop strikes said horizontal movable element the detent is operated to release said bar with a minimum of resistance and the switch and clutch are 35 opened by the movement of said bar under the action of the spring acting thereon.

5. A combination according to claim 3, in which the means for operating said switch and clutch comprise arms on said switch and clutch 40 extending into the path of said bar.

6. A combination according to claim 3, in which the means for operating said switch and clutch comprise arms on said switch and clutch extending into the path of said bar, means on 45 said bar engaging said arms in a direction to move said arms to open the switch and clutch when the bar is released by said detent, and springs for moving said arms to close said switch and clutch when the bar is moved, against the 50 tension of the spring acting thereon, by the manual key-lever, said latter (bar-actuating) spring being of sufficient strength to overcome both of said arm-moving springs.

7. A combination according to claim 3, wherein said means for connecting the motor to the carriage further comprises a drum driven by the motor through the clutch, a cord wound on said drum and adapted to be connected to the carriage, and a light winding-spring acting to turn 55 said drum in the same direction as it is turned by the motor and to maintain a tension on said cord when said clutch is open and the carriage is 60 moved back and forth manually.

8. A combination according to claim 3, said 65 mounting means including a single flat plate, separate from a typewriter frame, and means thereon for supporting said motor, clutch, bar, key-lever, and detent.

9. A combination according to claim 3, said 70 mounting means, including a single flat-plate, separate from a typewriter frame, and having portions lying outside of an area corresponding to the area of the underside of a typewriter frame, and means attached to the portions of 75

said plate in said outside area for supporting said motor, clutch, bar, key-lever and detent.

10. A combination according to claim 3, in which said means for connecting the motor to the carriage comprises reduction gearing between said motor and clutch, said reduction gearing consisting of gears of a type which are capable of transmitting turning movement with equal facility in either direction, whereby the shock of impact of a carriage which is stopped while connected through said connections to the motor will transmit an impulse through said connections in an opposite direction to the direction of action of the motor, the impulse acting through said gears to reverse the direction of turning of the motor and thereby relieve the pressure between the engaged parts of the clutch and ease the opening of the clutch by the spring acting on said bar.
20. 11. Carriage return mechanism for typewriters comprising a single flat plate, separate from a

typewriter frame and having portions lying outside of an area corresponding to the area of the underside of a typewriter frame, a motor, and a drum for winding a cord adapted to be attached to the carriage of a typewriter, said motor and drum being attached opposite one another to the portions of said plate in said outside area at the same side running from front to rear, a shaft running the length of said frame between said drum and motor, means including a clutch between said motor and shaft, and means for starting and stopping said motor comprising a switch on said plate, a bar on said plate running parallel to said shaft lengthwise of said plate from front to rear, arms on said clutch and switch extending into the path of movement of said bar, and a manual key-lever on the front portion of said plate adjacent the front end of said bar for actuating said bar.

FREDERIC W. LE PORIN. 20.
